DISPENSER FOR LAWN CARE CHEMICALS

Karl R. Stucky, 9225 N. 5th St.,
Phoenix, Ariz. 85020

Filed June 18, 1973, Ser. No. 380,864

Term of patent 14 years

Int. Cl. D23—01

U.S. Cl. D23—3

FIG. 1 is an isometric view of a dispenser for lawn care chemicals showing my design;

FIG. 2 is a side view thereof; and

FIG. 3 is a rear elevation thereof.

I claim:

The ornamental design for a dispenser for lawn care chemicals, as shown.
